UNITED STATES PATENT OFFICE.

RUDOLF DE CLEYN BREM, OF DUREN, AND JOHANN KEPPELER, OF BIRKESDORF, GERMANY, ASSIGNEES TO GEBRÜDER SCHOELLER, OF DUREN, GERMANY.

APPARATUS FOR PRINTING YARNS.

Application filed July 14, 1923. Serial No. 651,510.

To all whom it may concern:

Be it known that we, RUDOLF DE CLEYN BREM, a citizen of Holland, residing at Duren, No. 39 Kreuzstrasse, Rhenish Prussia, Germany, and JOHANN KEPPELER, a citizen of Germany, residing at Birkesdorf, No. 10 Durenerstrasse, Rhenish Prussia, Germany, have invented certain new and useful Improvements in an Apparatus for 10 Printing Yarns; and we do hereby declare the following to be a full, clear, and exact description of the invention, such as will enable others skilled in the art to which it appertains to make and use the same.

15 This invention relates to an apparatus for printing yarns of the kind with which the yarns are either wound in adjacent windings around the solid impermeable peripheral wall of a drum or stretched on a 20 suitable impermeable table and then printed by a printing roller moved transversely with relation to the windings.

The invention has for its object to provide an apparatus of the kind stated in which 25 the surface of the impermeable drum or table is covered by a layer of small thickness which is permeable to the colour yet non-absorbent and which constitutes the supporting face for the yarn to be printed.

30 According to the invention, the permeable yet non-absorbent layer preferably consists of a metallic cloth which is applied to the drum or table surface. This cloth forms an elastic bearing sheet for the yarn and 35 permits of a shockless working of the apparatus.

The accompanying drawing illustrates, by way of example, an embodiment of the subject-matter of the invention.

40 Fig. 1 is a partial axial section of a yarn-drum constructed in accordance with the invention, in combination with the printing and equalising rollers which are shown in end elevation;

45 Fig. 2 is a partial side elevation of the drum on an enlarged scale, and

Fig. 3 is a perspective view of a portion of the drum.

The apparatus shown comprises, in general, a yarn-drum *a*, a printing roller *b* adapted to revolve in the ordinary colour trough *c* and a plurality of equalising or spreading rollers *d*.

The drum *a* has a solid peripheral wall

*a*¹ which is primarily covered by an oiled cloth *f* around which is wrapped a cloth *g* consisting of a wire-fabric and designed to have the yarns *h* wound around it.

The printing roller *b* and the equalising rollers *d* are arranged for movement parallel with relation to the axis of the drum *a*. The rollers *b*, *d* are pressed against the yarns *h* by springs. These as well as the means for supporting and actuating the yarn-drum, the printing and equalising rollers may be of any approved construction and, therefore, are not shown in the drawing.

It will be seen that, with a drum of the described construction, the colour applied to the yarn *h* by the printing roller *b* is allowed to pass inwardly to and through the permeable layer *g* so that also the side of the yarn bearing against said layer will be moistened directly by the colour applied, whereby a perfect colouring of the yarn throughout and a uniform pattern as regards the shade is obtained. At the same time, no colour will be wasted in as much as the same is subjected in the permeable yet non-absorbent layer *g* to an undulatory movement caused by a vacuum which is produced in the operation of spreading the colour applied, the said undulatory movement being so that the colour will follow the implement used to spread the colour applied. The waves or undulations extend from the outer surface of the layer of yarns *h* inwardly on to the ground or inner surface of the layer *g* and then outwardly again on to the surface of the layer of yarns *h*. Owing to the possibility of the colour evading inwardly, a shifting of the colour by the printing roller over the yarns will be prevented, so that the liability of colour ridges being formed at the colour-streaks produced by the printing roller is materially reduced. Therefore, an intensive rubbing of the colour by spreaders for the purpose of evenly colouring the yarns throughout may eventually be dispensed with and the spreading operation substituted by a rolling-out operation.

Having thus described our invention, what we claim as new and desire to secure by Letters-Patent, is:—

1. In an apparatus for printing yarns, a solid impermeable yarn-carrier covered by a

permeable yet non-absorbent layer of small thickness designed to form the supporting face for the yarns to be printed.

2. In an apparatus for printing yarns, a solid impermeable yarn-carrier covered by a metallic cloth which is permeable to the printing colour but non-absorbent and designed to form the supporting face for the yarns to be printed.

3. In an apparatus for printing yarns comprising a yarn-drum having a solid impermeable peripheral wall, the outer surface of this wall being covered by a permeable yet non-absorbent layer of small thickness

designed to form the supporting face for the yarns to be printed.

4. In an apparatus for printing yarns comprising a yarn-drum having a solid impermeable peripheral wall, a permeable yet non-absorbent metallic fabric wrapped around the peripheral surface of the drum and designed to constitute the supporting face for the yarns to be printed.

In testimony whereof we have signed our names to this specification.

RUDOLF DE CLEYN BREM,
JOHANN KEPPELER.
